CRACKING OF HYDROCARBON OILS WITH
FINELY DIVIDED HEAT RESISTANT NON-
CATALYTIC MATERIALForrest H. Blanding, Elizabeth, N. J., assignor to
Standard Oil Development Company, a corpora-
tion of Delaware

Application December 10, 1943, Serial No. 513,671

3 Claims. (Cl. 196—55)

1

The present invention relates to improvements in the thermal cracking of hydrocarbons, and more particularly it relates to vapor phase cracking in the presence of an added solid inert material.

The demand for high octane number gasoline has necessitated the construction of a large number of new catalytic cracking plants. However, some high quality motor gasoline and even aviation gasoline has been produced by thermal cracking, particularly by those processes which operate at high temperatures. In this type of operation the quantity of normally gaseous hydrocarbons formed is high, and it so happens that the requirements for a number of normally gaseous hydrocarbons is also great at the present time, that is to say, there is a definite need for the olefins such as ethylene, propylene, butylene, etc., for these materials may be used to alkylate an isoparaffin such as isobutane to form an alkylate, so-called, a very valuable agent useful in the manufacture of 100 octane aviation gasoline. In addition, olefins such as butylene are dehydrogenated in large quantities to form butadiene, a substance which is a valuable raw material in the manufacture of synthetic rubber and rubber substitutes. It has also been shown that highly concentrated aromatic oils can be made by intensive thermal cracking. These fractions have been vitally useful in modern aviation gasoline manufacture.

According to my present process, I subject a hydrocarbon oil such as a gas oil to severe cracking conditions in the presence of a solid inert material and I obtain a product which is high in aromatics. Very desirable constituents are thus available for use as an aviation gasoline.

In a preferred method of operating my process, I inject cold oil directly into a fluidized mass of inert refractory material and heat the oil to severe cracking conditions in a relatively short period of time. The oil may then be quenched after a short reaction or contact time to prevent undesired side reactions.

The main object of my present invention is to produce a high quality gasoline by thermal cracking of feed stock under conditions such as to produce increased quantities of aromatics.

Another object of my invention is to thermally crack a hydrocarbon oil under conditions such as to produce large quantities of olefins.

A third object of my invention is to design a thermal cracking plant adapted to operate at temperatures as high as 2000° F. and employing a minimum of expensive and special alloy steels.

2

Another object of the invention is an operable and feasible process to accomplish severe oil cracking. In connection with this object I desire to emphasize that in normal cracking units using coils or drums, coke is formed at comparatively low temperature (around 900° F.) which limits the severity of the operation. This objection can be overcome only by steam cracking or cracking with diluents at very low pressures. The addition of steam and use of low pressures necessitate large coils or drums made from highly critical materials.

Other and further objects of my invention will appear from the following more detailed description and claims.

In the accompanying drawing I have shown diagrammatically an apparatus in which a preferred modification of my invention may be carried into effect.

Referring in detail to the drawing, 1 represents a reactor lined with brick or other refractory material, which is in the form of a cylindrical vessel with an upper and lower conical section. In reactor 1 I maintain a body of fluidized solid material which does not easily disintegrate, such as crushed coke, powdered coal, ground pumice, sand, or any highly refractory non-catalytic material (from the standpoint of catalytic cracking). The solid material is finely divided and may be in the form of a powder but preferably is in the form of particles or aggregates of appreciable size up to $\frac{1}{4}$ inch average particle size. I maintain the solid material in the fluidized state referred to by forcing gases, including oil vapors, upwardly in the vessel at a velocity of from 0.5—15 feet per second. I prefer to use the larger size particles, say at least $\frac{1}{8}$ inch average size, because this permits a higher gas or vapor velocity in the reactor since the greater the particle size the greater the vapor velocity must be to maintain the solids in fluidized state. I may discharge steam through line 10 into the reactor under such pressure conditions that it will flow upwardly in conjunction with hydrocarbon vapors, also contained therein, within the limits of velocity indicated. I also inject into the reactor 1 through line 12 cold (atmospheric temperature) gas oil such as, for instance, an East Texas gas oil boiling within the range of from 400—800° F. and having an A. P. I. gravity of about 25°. I may also, however, preheat the oil to 600 F. or higher before introducing it into the reactor.

The heat necessary for the conversion is acquired by the oil from the solid, fluidized mate-

rial and by preheating. The oil, of course, under the conditions stated undergoes cracking to form a vapor and coke, coke being deposited on the solid material. The vapors are withdrawn overhead through line 15 and are quenched, fractionated, condensed and collected in the usual manner. Since, however, the vapors issuing from the bed of solid material in the reactor 1 are at an extremely high temperature, I prefer to quench them by injecting through line 14 a 10 quantity of fluid such as water or steam, whereupon the vapors may be cooled, say, to 700° to 1100° F., in line 15. In other words, I so operate my process that the oil is heated rapidly to a high temperature and permits only a relatively short 15 contact time, or residence time, say of the order of up to 5-10 seconds, preferably below 2 seconds or even one second, because short contact time prevents or suppresses undesired side reactions. Hence, my preferred method of operating is to heat the feed oil rapidly to a high temperature, say, around 1800° F., preferably at a temperature between about 1200-1500° F., pass the vapors through the fluidized mass at a high velocity, say, up to 15 feet per second, and quench the vapors as they emerge from the reactor. To prevent carry-over of solid in large quantity with the exit vapors, the particle size of the solid material must be relatively large, viz., of the size previously indicated. From line 15 I pass the vapors through a waste heat boiler 16 where they are further cooled to a temperature of about 250° F. up to 600° F., whereupon they are withdrawn through line 18 and passed into a fractionator 20. From fractionator 20 normally gaseous hydrocarbons may be withdrawn through line 22, a gasoline fraction withdrawn through line 24, a fraction boiling within the light gas oil range, say up to 600° F., withdrawn through line 26, and finally a bottoms fraction is withdrawn through 30 line 28 and recycled to 12. A portion of this latter fraction may be withdrawn continuously from the system through line 30.

Referring back to the reactor 1, the solid material which of course accumulates coke in the cracking operation is continuously withdrawn through a drawoff pipe 6 carrying a flow control valve 8, and this material is discharged into a mixing device 9 where it is mixed with air or other oxygen containing gas from 11 and then conveyed pneumatically via line 32 into a burning or combustion zone 33. In zone 33 secondary air may if necessary be injected through a line 35, and the air or other oxygen-containing gas thus introduced at the high temperatures involved causes combustion of the tarry material or coke deposited on the solid material as a result of the cracking in reactor 1. In combustion chamber 33 the gases and the solids flow concurrently upward causing the linear velocity of the gases to be of the order of 20 ft. per second, or higher, if necessary. The suspension of regeneration gas and/or regeneration fumes containing the solid material is withdrawn through line 40 and passed through a plurality of separating devices 42 wherein the solids are separated from the regeneration fumes via lines 43, and the solid is then conveyed by gravity to a feed hopper 50 from which hopper 50 it may be conveyed by gravity into the reactor 1, thus completing a cycle of 70 operations.

As indicated previously, a good way to operate my process is to lay down enough coke in the solid material in reactor 1 by the cracking that when this coke is burned in chamber 33, 75

enough heat will be absorbed by the solid material to preheat the oil, to vaporize and superheat the said oil and to supply the endothermic heat. If desired, extraneous oil or other combustible material may be burned with the formed coke in combustion chamber 33. Further, heat may be recovered from the hot cracked vapors and employed to preheat the oil in suitable heat exchangers.

While I have described in detail the method of processing a gas oil, it will be understood that I may inject a heavy oil such as a reduced crude directly into the reaction zone. As indicated, the oil injected need not be at atmospheric temperature but may be preheated somewhat, say to a temperature of 400-800° F., but the main bulk of the heat is supplied by contacting the oil with the hot solid material which may have a temperature of 2000-2200° F. and preferably has a temperature of at least 1200° F.

I have shown means wherein oil is sprayed into the combustion zone 33 through a line 34. This additional oil is added where insufficient coke is laid down on the particles during cracking to supply upon combustion the heat necessary for the process. Also, I may add powdered coal or some other combustible material such as a normally gaseous hydrocarbon or CO, or any other combustible material. Coal or coke may be used as the inert material and added or withdrawn as required. I have shown an "upflow" combustion chamber.

Numerous modifications of my invention may be made by those familiar with this art without departing from the spirit thereof.

I claim:

1. A continuous process for cracking hydrocarbon oils, which comprises providing a mass of finely divided, non-catalytic, heat resistant material in a reaction zone, maintaining said finely divided material in fluidized condition, injecting an oil to be cracked directly into said mass of fluidized material thereby causing cracking of said oil, the temperature in said reaction zone being within the range of 1200 to 2200° F., supplying a quenching material immediately above the fluidized mass to reduce the temperature of the products arising therefrom, continuously withdrawing finely divided material containing contaminants deposited thereon as a result of the cracking, conveying the finely divided material directly to a combustion zone, causing the contaminants on the finely divided material to be consumed by combustion in the combustion zone, withdrawing the finely divided material from the combustion zone and returning it directly and substantially uncooled to the reaction zone for effecting vaporization and cracking of further amounts of oil.

2. A continuous process for cracking hydrocarbons, which comprises providing a mass of finely divided, heat resistant, non-catalytic material in a reaction zone, maintaining said mass in fluidized condition, injecting an oil to be cracked directly into the fluidized mass in said zone in at least partly liquid condition as it enters said zone, the temperature in said reaction zone being within the range of 1200 to 2200° F., cracking the oil in said zone in contact with the fluidized mass which is at a vaporizing and cracking temperature, supplying a quenching material to the reaction zone above the fluidized mass to reduce the temperature of the products arising therefrom, continuously withdrawing finely divided material containing contaminants de-

posited thereon as a result of the cracking, conveying the finely divided material directly to a combustion zone, causing the contaminants on the finely divided material to be consumed by combustion in the combustion zone, withdrawing the finely divided material from the combustion zone, and returning it directly and substantially uncooled to the reaction zone for effecting vaporization and cracking of further amounts of oil.

3. A continuous process for treating hydrocarbons by intensive thermal cracking to produce increased quantities of aromatics and normally gaseous olefins which comprises providing a mass of finely divided, heat resistant, non-catalytic material in a reaction zone, maintaining said mass in fluidized condition, injecting an oil to be cracked directly into the fluidized mass in said zone in at least partly liquid condition as it enters said zone, cracking the oil in said zone for a period of time less than about 10 seconds in contact with the fluidized mass which is at a vaporizing and cracking temperature, supplying a quenching material to reduce the temperature of the products arising from the reaction zone, continuously withdrawing finely divided material containing contaminants deposited thereon as a result of the cracking, conveying the finely divided material directly to a combustion zone, causing the contaminants on the finely divided material to be consumed by combustion in the combustion zone, withdrawing the

5 finely divided material from the combustion zone, and returning it directly and substantially uncooled and at a temperature within the range of 1200 to 2200° F. to the reaction zone for effecting vaporization and cracking of further amounts of oil.
